(57) **CLAIM**

We claim the ornamental design for a measurement device, as shown and described.

DESCRIPTION

FIG. 1 is a front top perspective view;

FIG. 2 is a front view;

FIG. 3 is a rear view;

FIG. 4 is a first side view;

FIG. 5 is a second side view;

FIG. 6 is a top view;

FIG. 7 is a bottom view;

FIG. 8 is a front bottom perspective view; and,

FIG. 9 is a rear bottom perspective view.

The broken lines shown in FIG. 1-FIG. 8 are not part of the claimed design.

References to “side”, “top”, “front”, “rear” and “bottom” in the figure descriptions are not meant to require certain in-use orientation; a measurement device according to the claimed design may be used in any orientation.
